UNITED STATES PATENT OFFICE

BENJAMEN F. STIEBER, OF ROCKSPRINGS, TEXAS

BUTTER SLICER AND CONTAINER

Application filed December 27, 1929. Serial No. 416,906.

This invention relates to a combined refrigerator and dispensing apparatus primarily designed for the accommodation of butter or ice-cream which may be dispensed and served in block and brick formations respectively.

Another object of the invention resides in the provision and arrangement of a cutting element disposed at the discharge or dispensing end of the refrigerator.

An additional object of the invention embodies an operating lever for the cutting element.

More specifically stated the operating lever and cutting element are adjustably mounted with respect to each other and the discharge end of the refrigerator to facilitate the cutting and dispensing of the preserved contents of the refrigerator in uniform size.

With the above and other objects in view, the invention further consists of the following novel features and details of construction, to be hereinafter more fully described, illustrated in the accompanying drawings and 25 pointed out in the appended claims.

In the drawings:

Figure 1 is an elevation of the present invention partly broken away adjacent the base thereof;

Figure 2 is a fragmentary longitudinal sectional view through the invention;

Figure 3 is a horizontal sectional view taken on line 3—3 of Figure 2;

Figure 4 is a horizontal sectional view taken on line 4—4 of Figure 2; and

Figure 5 is a vertical sectional view taken on line 5—5 of Figure 2.

Referring to the drawings in detail wherein like characters of reference denote corresponding parts, the reference character 10 indicates generally the casing of my form of refrigerator and which may be constructed of metal, porcelain and the like and is supported at its lowermost end upon a base plate, indicated as at 11.

As shown in Figures 3 and 4 of the drawings, the refrigerator is of circular form and it is therefore necessary to provide an annular groove 12 at the upper side of the base plate 11 to accommodate the lower periphery

of the refrigerator casing. The bottom wall 13 of the refrigerator, spaced for an appreciable distance above the base plate 11, carries a form of container, such as indicated at 14, centrally thereof and which projects upwardly an appreciable distance within the interior of the refrigerator. The container, in the present application of the invention in the containing and dispensing of butter, is large enough to conveniently accommodate the customary quarter pound lengths of butter in package form and are to be disposed in end to end relation in the manner suggested in Figure 1 of the drawings. That portion within the refrigerator surrounding the container 14 is to be packed with cracked ice or may conveniently accommodate the coil of a modern type of iceless refrigerator. The top of each the refrigerator proper and container 14 are closed by lids 15 and 16 respectively.

The operating lever, mentioned in the foregoing, and as indicated at 17, is projected within the horizontally disposed slot 18 in the refrigerator casing below the bottom 13. A bolt 19, carried by the bottom 13, provides the pivot mounting for the innermost projecting end of the operating lever.

A band 20 of arcuate formation having a knob 21 at an intermediate point in the length thereof and vertically disposed slots 22 adjacent its ends accommodate the shanks 23 of bolt members carrying wing nuts 24. The upper edge of the band 20 is designed for engagement with the under surface or side of the operating lever 17 and which in conjunction with a nut 25 carried upon the shank 19 will regulate the clearance between the bottom wall 13 and the operating lever and preserve uniformity as to parallel relation.

A cutting element 26 reposing against the under side of the bottom wall 13 and extended immediately beneath the discharge end of the container 14 is adjustably connected at its ends through the instrumentality of bolt members 27 with appropriate portions of the operating lever 17. The clearance or distance between the operating lever 17 and the cutting element 26 regulates the thickness of the cut and when oscillated

across the discharge end of the container 14 will successively cut off squares of butter of uniform size.

The operating lever 17 is enlarged, as at 28, immediately adjacent that portion thereof which is to be disposed beneath the discharge end of the container 14. The lowermost projecting end of the immediate length of butter is initially disposed upon the upper side of the enlargement 28 and due to the fact that the remaining portion of the butter is held stationary, the cutting element 26 when being brought into contact therewith will sever the projecting end of the length of butter and automatically discharge same through an opening 29 provided in the enlargement 28 upon the next succeeding stroke of the operating lever. The remaining length of butter is held against further dropping upon the upper side of the cutting element 26 until the operating lever is shifted to its utmost in the cutting direction at which time the aforementioned length of butter will drop downwardly, equivalent to the predetermined slicing thickness and repose upon the other side of the enlargement 28.

Although I have shown and described my invention as being designed for the containing, preservation and dispensing of butter, 30 it is obviously apparent that ice-cream and other articles of food may be likewise accommodated and dispensed in similar manner with equal effect.

As shown in Figures 2, 3 and 5 of the drawings, the casing 10 is provided with an entrance opening 30 beneath the bottom wall 13 of the refrigerator proper through which plates or butter dishes may be projected to accommodate pats or squares of butter as dispensed.

The invention is susceptible of various changes in its form, proportions and minor details of construction, and the right is herein reserved to make such changes as 45 properly fall within the scope of the appended claims.

Having described the invention, what is claimed is:—

1. A refrigerated food dispensing apparatus having a discharge compartment therebeneath, an operating lever pivotally mounted within the compartment having sliding food supports selectively registerable therewith, a cutting element carried by and 55 operable in conjunction with the lever between the supports, and adjusting means for the lever and cutting element.

2. A refrigerated food dispensing apparatus in communication with a food container and discharge compartment therebeneath, an operating lever pivotally mounted for oscillatory movement within the compartment below the food container having food supports disposed upon opposite sides 65 of a common discharge opening, a cutting

element carried by the lever centrally of and slightly above said opening, and adjusting means for the lever and cutting element for cutting the food in uniform proportions.

In testimony whereof I affix my signature.

BENJAMEN F. STIEBER.
